UNITED STATES PATENT OFFICE.

HOWELL D. PRATT, OF PHILADELPHIA, PENNSYLVANIA, ASSIGNOR TO LINK-BELT COMPANY, OF CHICAGO, ILLINOIS, A CORPORATION OF ILLINOIS.

LOADING APPARATUS.

1,343,746.

Specification of Letters Patent. Patented June 15, 1920.

Application filed June 13, 1919. Serial No. 303,855.

To all whom it may concern:

Be it known that I, HOWELL D. PRATT, a citizen of the United States, residing in Philadelphia, Pennsylvania, have invented 5 certain Improvements in Loading Apparatus, of which the following is a specification.

My invention relates to loading apparatus and especially apparatus for loading cars, 10 boats, etc.

One object of my invention is to provide a simple and effective means for removing material from piles and discharging it into an elevator of a loading apparatus.

15 A further object of the invention is to provide means for moving the anchor of the material-removing apparatus so that as the pile of material diminishes the anchor can be shifted in order that the removing 20 device will progressively attack the pile and push or drag the material of the pile toward the loading apparatus.

A still further object of the invention is to mount the operating means of the removing 25 apparatus on the frame of the loader so as to insure the proper feeding of the loading apparatus with material.

In the accompanying drawings:

Figure 1 is a diagrammatic plan view 30 showing the loader and the mechanism for removing material from a pile and carrying it to the loader;

Fig. 2 is an enlarged side view of the loader;

35 Fig. 3 is a side view illustrating the mechanism for delivering material to the loader;

Fig. 4 is a plan view of the loader;

Fig. 5 is a detached view illustrating the clutch mechanism;

40 Fig. 6 is a perspective view of the scraper; and

Fig. 7 is a view of a modification.

1 is the loader having a bucket elevator 2, of any suitable type. This loader is 45 mounted on wheels 3. Carried by the frame 4 of the loader is a shaft 5 on which are mounted two drums 6 and 7, in the present instance, which are arranged to be coupled to the shaft by the clutch 8. 9 is 50 a rope. One end of the rope is attached to one drum and the other is attached to the other drum. This rope passes around a sheave 10 carried by an anchor 11. Secured to this rope is a scraper 12 which is 55 made as shown in Fig. 6, and is arranged

to travel over the surface of the material and drag a certain quantity of the material to the delivery point of the loader. The anchor 11 is secured to the rope 13, which passes around guide sheaves 14 at 60 fixed points so that the anchor rope surrounds the pile of material to be removed, as shown in Fig. 1. The two ends of the rope 13 are attached to a drum 14^a of a windlass 15, which can be turned by a handle 16 so that on turning the windlass in one direction the anchor will be shifted in one direction and when it is turned in the opposite direction the movement of the anchor will be reversed. Consequently, if 70 the scoop and its load be located at one side of a pile *a* of material, as the pile is lowered by the action of the scraper the anchor rope 13 can be moved so as to shift the anchor 11 toward the pile in order that the 75 scraper may make an advanced cut into the pile. This can be carried out until the entire pile is removed. On the other hand, if the anchor be placed so that the scraper and its load will travel over the center of 80 the pile, then the anchor can remain in this position until the central portion of the pile is removed and the sides of the two sections of the pile will flow into the path of the scraper. Then the anchor can be 85 shifted, first to the right and then to the left, to remove the entire pile.

The detail construction of the apparatus is clearly shown in Figs. 2, 3 and 4. The frame 4 of the loading apparatus is supported on a platform 17 and the axle 18, on which the wheels 3 are mounted, is secured to this platform, and the axle 19, on which are the two trailer wheels, is pivotally mounted on the frame so that when it is 90 wished to shift the apparatus it can be readily accomplished. The apparatus is anchored in any suitable manner in a fixed 95 position.

The conveyer 2 consists of an endless 100 chain 21 having buckets thereon, which pass around a head wheel 22 and a foot wheel 23. This conveyer is mounted on a frame 24 pivoted at 25 at the upper end to the main frame 4, while the lower end is 105 adjustable. In the present instance, I have shown a drum 26 on a shaft 27 adapted to bearings on the platform 17, and a chain 28 attached to the inner end of a beam 29 is secured to the drum. A shaft 30 is geared 110

to the drum shaft 27 through a worm gear 31 and has a handle 32 by which it is turned, so that on turning this handle the lower end of the conveyer can be projected, or retracted, as desired.

The detail of the clutch mechanism is as follows:—The frame 4 is extended as at 33 and on this extension are the bearings 34 for the shaft 5 on which are loosely mounted the two drums 6 and 7. On the drum 6 is one portion 35 of a friction clutch and on the drum 7 is a like portion 36 of a friction clutch. The clutch 8 has, in the present instance, two beveled portions 37 and 38, 15 which can be moved into frictional contact with the portions 35 or 36 of the drums. In order to shift the clutch 8, I provide a shifting rod 39 having handles within easy reach of the operator at each side of the machine. This shifting rod is attached to a shifter 40 pivoted at 41 to a cross beam attached to the extension 33, and is in engagement with the clutch 8 so that on moving the shifting bar 39 in one direction the 20 clutch will be in engagement with one drum and on shifting it in the opposite direction the clutch will be in engagement with the other drum. By this means, the movement of the rope 9 is reversed. In the present 25 instance, the upper rope passes around a sheave 43 on a post 44 and the lower rope passes around a sheave 45 on an extension 46. Carried by the frame 4 is a trough 52, which catches any material that falls from the elevator and returns it to a point in the 30 path of the buckets. In the present instance, the buckets discharge into a chute 47 carried by the upper end of the frame 4. This chute may have an extension, if desired, depending upon the location of the 35 elevator in respect to the carrier to be loaded.

48 is a motor which drives the shaft 49 around which passes the driving chain 50 45 for driving the elevator and also around which passes the chain 51 for driving the shaft 5. The detail construction of the apparatus may be modified without departing from the essential features of the invention.

50 If, for instance, the loader be located adjacent to the railway track on which the cars are run to be loaded and there is a considerable pile of material beyond the track, then the loader is placed in position so as to 55 discharge directly into a car and the anchor rope 13 extends around the pile and the sheaves 14 anchored at different distances apart. The anchor 11 carrying the sheave 10 is attached to the anchor rope 13 60 at a given point and the windlass 15 is located so as to be clear of the pile and of the loading apparatus. The scraper and its ropes are placed in position so as to remove material from the pile and discharge it at 65 the foot of the conveyer of the loading ap-

paratus. The operator actuates the shifting bar 39 so that the clutch will first engage one drum in order to move the scraper toward the loader and then throws it into engagement with the other drum so as to 70 move the scraper away from the loader so that the material is fed to the loader intermittently by the reciprocating scraper. Different forms of scrapers may be used, but I prefer to use the scraper illustrated in 75 the drawings, and which is clearly described and claimed in the patent granted to me on the 14th day of May, 1918, No. 1,266,153.

When the scraper has removed material from the pile to such an extent as to reduce 80 its capacity, then the anchor 11 is shifted by operating the windlass 15 so that the scraper will travel in another path and will remove additional material from the pile and the movement of the anchor will be 85 continued until the entire pile has been removed.

In Fig. 7, I have illustrated a construction in which a series of scrapers is shown attached to a single rope. The rope is reciprocated and the amount of reciprocation will depend upon the distance apart of the 90 scoops, so that one scoop will discharge material at such a point that it can be taken up by another scoop and finally delivered at 95 the discharge point.

The apparatus that I employ is comparatively simple, and is within the cost of the small shipper. At the same time, it will do the work of a more expensive and intricate 100 machine. The apparatus is flexible, as the anchor rope can be lengthened or shortened, according to the size of the piles.

By carrying the operating drums for the 105 scraper on the frame of the loading apparatus, a single motor can operate the elevator of the loading apparatus, as well as the mechanism of the scraper.

In Fig. 3, I have shown a drag 53 having teeth which engage the material and loosen 110 it so that it can be readily scraped. This drag is attached to the rope 9 at the rear end of the scoop in the present instance.

I claim:

1. The combination in a loading apparatus, of a frame, said frame having horizontal bars fixed to it and forming an extended elevated supporting structure; an elevator carried by the frame back of said extension; a shaft on the extended portion of the 115 frame; two drums loose on the shaft; a clutch arranged to turn with the shaft; means for shifting the clutch so as to engage either of said drums; a rope connected to said drums; a sheave around which the 120 rope passes; an anchor for the sheave located distant from the drums; and a scraper carried by the rope so that on alternately reversing the movement of said rope the 125 scraper will remove material from a pile 130

and deliver it to the receiving end of said elevator.

2. The combination in a loading apparatus, of a vertical frame, said frame having 5 horizontal bars fixed to it at a point intermediate of its height and forming an extended elevated supporting structure; an elevator mounted on the frame back of said structure; means for driving the elevator; 10 a shaft mounted in bearings on the extension; means for driving the shaft; two drums loose on the shaft; an intermittent clutch arranged to engage either of the drums; a shifter for the clutch; a rope passing around each drum and passing through 15 a sheave at a point distant from the shaft; an anchor for the sheave; a scraper secured to the rope and arranged to scrape material toward the loader; and a unitary winding

drum to which both ends of the rope are 20 connected for shifting the position of said anchor.

3. The combination in a loading apparatus, of a bucket elevator for lifting material to a discharge point; a frame in which the 25 elevator is mounted, said frame having an elevated horizontal extension at one end located in advance of the elevator and a substantial distance above the receiving end thereof; a scraper; and means on said elevated extension for operating the scraper so that it can be located to remove material from a pile and carry it toward the elevator in order that said elevator may remain in a 30 fixed position.

In witness whereof I affix my signature.

HOWELL D. PRATT.
